UNITED STATES PATENT OFFICE.

FRED JAMES WESTROPE, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE STRIKER PLATE.

Application filed December 15, 1924. Serial No. 756,095.

This invention relates generally to striker plates and refers more particularly to those designed for use in connection with the movable bolts of vehicles door locks and latches.

One of the essential objects of the invention is to provide a plurality of striker plates that are preferably arranged in tandem and are adapted to be alternately engaged by the bolt of the lock for holding the door in either a partially closed position or in a fully closed position with respect to a suitable door jamb.

Another object is to provide a striker plate of this type that may be readily adjusted without interfering with the usual trimming material of the vehicle body for taking up wear and preventing rattling.

Another object is to provide an adjustable striker plate with suitable securing elements which are arranged in such a way that they cannot be used to adjust the striker plate but can effectively hold the same in any adjusted position.

A further object is to provide a strong and durable striker plate construction that comprises relatively few parts and can be manufactured at a comparatively low cost.

With the above and other objects in view, the invention consists of certain novel features of construction, combinations and arrangements of parts as will be more fully described and particularly pointed out in the appended claims.

In the accompanying drawings;

Figure 1 is a fragmentary side elevation of a door jamb with striker plates embodying my invention attached thereto.

Figure 2 is a cross-sectional view taken on the line 2—2 of Figure 1.

Figure 3 is a top plan view of the retainer plate.

Figure 4 is a top plan view of the inner adjustable striker plate.

Figure 5 is a top plan view of the outer striker plate.

Referring now to the drawings in which like characters of reference designate corresponding parts throughout the several views, the numeral 1 designates a door jamb, preferably of a vehicle body. This jamb may be formed of any suitable material and may be any shape desired, however it is

preferably formed of two sheet metal stampings 2 and 3 respectively. As shown, the stamping 3 is preferably channel-shaped in cross-section and is provided at its forward edge with a laterally extending flange 4, while the stamping 2 is also preferably channel shaped in cross section and has one flange 5 thereof overlapping the lateral flange 5 of the stamping 3. These overlapping flanges may be secured together by any suitable means but are preferably welded together.

In order that a swinging door 6 may be held partially closed or fully closed with respect to the door jamb 1, I preferably provide two striker plates 7 and 8 respectively that are arranged in tandem upon the door jamb 1 and are adapted to be engaged by the movable bolt 9 of a lock (not shown) carried by the door 6.

The striker plate 7 is preferably formed of sheet metal and is preferably permanently secured to the jamb section 2 while the striker plate 8 is also preferably formed of sheet metal but is adjustable transversely of the section 3 for taking up wear and preventing the bolt 9 from rattling. As shown, the striker plate 7 is wedge-shaped in form and is provided at its opposite sides with the outwardly extending attaching ears 10 which are secured to the jamb 5 of the jamb section 2.

The striker plate 8 is also wedge-shaped in form but is movable longitudinally of an elongated opening 10' that extends transversely of the jamb section 3 from the inner edge of the lateral flange 4 to a point adjacent to the rear flange 11. For supporting the striker plate 8 in the opening 10', I provide a retainer plate 12 that bridges the opening 10' and is permanently secured to section 3. As shown, this retainer plate 12 is riveted at its forward end to the lateral flange 4 of the section 3 and is provided at its rear end with a lateral flange 13 that is secured to the rear flange 11 of the section 3. Intermediate it ends, the retainer plate 12 is provided with a laterally extending substantially wedge-shaped projection 13 which extends into the hollow wedge-shaped striker plate 8 and is of such a size with respect to the striker plate 8 that sufficient clearance is provided for per-

mitting the striker plate 8 to be adjusted transversely of the jamb 1. In order that this adjustment may be accomplished without interfering with the usual trimming material (not shown) of the vehicle body, the inclined wall 14 of the striker plate 8 is provided with a longitudinally extending depressed portion 15 having an elongated slot 16 for receiving a suitable headed element such as a screw 17 that threadedly engages the inclined wall 18 of the laterally extending portion 13 of the retainer plate. As shown, the base 19 of the depressed portion of the striker plate is preferably arcuate shaped and engages a correspondingly shaped portion 20 of the inclined wall 14 of the lateral projection 13, however the arcuate portion 20 is preferably longer than the arcuate portion 19 so that it may form a bearing for the latter in any position to which the striker plate 8 may be adjusted transversely of the jamb 1.

To retain the striker plate 8 in adjusted position, the rear wall 22 thereof is provided at its lower end with an arcuate shaped rearward extension 23 that engages a correspondingly shaped arcuate portion 24 of the retainer plate 12 and is provided with a longitudinally extending slot 25 for receiving a suitable headed element such as a screw 26 which threadedly engages the arcuate shaped portion 24.

As shown, the arcuate portion 24 of the retainer plate is concentric with the arcuate portion 20 of the lateral projection 13 and the arcuate rearward extension 23 is concentric with the arcuate base portion 19 of the striker plate 8, consequently the screws 17 and 26 lie in converging planes and the heads therefor are tangential to the arcuate portions 19 and 23 respectively of the striker plate. Consequently these screws cannot be used to adjust the striker plate 8 but will effectively hold the same in any adjusted position.

In use, when the screws 17 and 26 are loosened, the striker plate 8 may be adjusted by hand to the desired position, whereupon the screws may be adjusted inwardly to hold the striker plate 8 in adjusted position. Thus the striker plate 8 may be readily adjusted without interfering with the usual trimming material of the body for taking up wear and preventing the bolt 9 from rattling. Moreover, the arrangement is such that the whole construction comprises relatively few parts which may be readily formed of sheet metal, consequently the cost of manufacturing such devices has been reduced to a minimum.

While it is believed that from the foregoing description the nature and advantages of the invention will be readily apparent, I desire to have it understood that I do not limit myself to what is herein shown and

described, and that such changes may be resorted to when desired as fall within the scope of what is claimed.

What I claim as my invention is:

1. A striker plate including an adjustable hollow wedge-shaped body, and a support for said plate having a substantially wedge-shaped portion projecting within the hollow body, and means for holding the body in adjusted position including an element extending transversely of said hollow body and projection. 70 75

2. A striker plate including an adjustable hollow wedge-shaped body having an extension, and a support for said plate having a substantially wedge-shaped portion projecting within the hollow body, and means for holding the body in adjusted position including a headed element extending transversely of said extension and support. 80 85

3. A device of the class described, including a retainer plate having a lateral wedge-shaped projection, and a substantially wedge-shaped striker plate adjustably mounted on said projection. 90

4. A striker plate including an adjustable wedge-shaped body, a retainer plate having a substantially wedge-shaped lateral projection extending within the wedge-shaped body, and a connection between said retainer plate and striker plate adapted to hold said striker plate in adjusted position. 95

5. A device of the class described, including a retainer plate having concentric arcuate portions, a striker plate adjustable longitudinally of said retainer plate having concentric arcuate-shaped portions slidably mounted on the arcuate-shaped portions of said retainer plate, and means carried by said retainer plate for holding said striker plate in adjusted position. 100 105

6. A striker plate including an adjustable body having concentric arcuate-shaped portions provided with elongated slots, and a retainer plate having concentric arcuate-shaped bearing portions for the arcuate portions of said striker plate, and means engageable with said slots and extending through said retainer plate for holding the striker plate in adjusted position. 110 115

7. A device of the class described, including a retainer plate having concentric arcuate-shaped portions, a striker plate adjustable longitudinally of said retainer plate on said arcuate-shaped portions, and means extending transversely of the arcuate-shaped portions of said retainer plate for holding said striker plate in adjusted position. 120 125

8. A device of the class described comprising a retainer plate having a lateral projection, intermediate the ends thereof, a striker plate adjustably mounted on said retainer plate and having a portion receiving said projection, and securing means for 130

said striker plate including means movable longitudinally in converging planes through both said striker plate and retainer plate.

9. A device of the class described comprising a retainer plate having a lateral projection, a striker plate adjustably mounted on said retainer plate and having a portion receiving said projection, and securing means for said striker plate including

headed elements movable longitudinally in converging planes through both said striker plate and retainer plate, said headed elements passing freely through said striker plate and threadedly engaging said retainer plate.

15

In testimony whereof I affix my signature.

FRED JAMES WESTROPE.
